TURNING-IN MACHINE FOR BOOKBINDERS

Johannes G. Ort, Cincinnati, Ohio, and Joseph R. Hibbard, Covington, Ky.

Application November 26, 1947, Serial No. 788,214

16 Claims. (Cl. 154—41)

1

Our invention relates to a turning-in machine in the book binding art for turning-in the covering material on the cover board of a book or the like.

In book binding, it is customary to cover the cover board which comprises the front and back of a book with covering material of either buckram, canvas, imitation leather, or any other well-known materials. The covering material is made slightly larger than the cover board and the projecting edges are turned up over the edges of the board and adhesively secured to the other side.

Normally this operation is done by hand, which of course, slows up the whole process of binding books. While there are machines for turning-in, as it is called, the edge of the cover material, they are usually only applicable when adjusted for books of a said predetermined size.

It is an object of our invention to provide a turning-in machine which may be used without readjustment on cover boards of various sizes.

It is a further object of our invention to provide a turning-in machine which will quickly and evenly turn-in the edge of the cover material and press it tightly against the cover board so that it will adhere and not come apart after rough handling.

It is a further object of our invention to provide a turning-in machine which has all of the advantages stated above and which will turn-in the cover material over the cover board on all four sides evenly and neatly.

A further object of our invention is to provide a turning-in machine which is relatively inexpensive to construct but which is extremely rugged and will operate continuously for a relatively long period.

These and other objects of our invention which will be set forth hereinafter or will be apparent to one skilled in the art upon reading the specifications, we accomplish by that certain construction and arrangement of parts of which we shall now describe an exemplary embodiment.

Reference is now made to the drawings which form a part thereof and in which:

Figure 1 is a front elevation of our turning-in machine from the operator's position.

Figure 2 is a plan view of our novel turning-in machine.

Figure 3 is a cross section of our novel turning-in machine taken on the section line 3—3 of Figure 1.

Figure 4 is a perspective view of a cover board with cover material underlying the same.

2

Figure 5 is a cross section of the upper portion of our turning-in machine taken on the section line 5—5 of Figure 1.

Figure 6 is an enlarged cross section of the operating portion of our turning-in machine showing the cover board and cover material in operating position.

Figure 7 is a plan view of a portion of the mandrel of our turning-in machine.

Figure 8 is a perspective view of the cover board with the material in place after it has been turned-in.

Briefly, in the practice of our invention, we provide a turning-in machine consisting of a rotating mandrel having projecting resilient ears tangentially positioned on the mandrel in a helical line around the same. The mandrel is rotated above a support for the cover board and underlying cover and is rotated so that the ears will wipe the upturned edge of the cover over and downward upon the surface of the cover board.

We provide also an abutment which assists the operator in starting the bend in the cover material as well as an abutment on the supporting frame to insure the correct positioning of the cover board and cover under the rotating mandrel.

Referring to the drawings, we provide a stand consisting of legs 1 having an upper frame 2 which supports a tilting table 3, fastened at one end to the frame 2 by the hinge 4. The opposite end of the table 3 is preferably supported on a rocker arm 5 pivoted at 6 to the frame 2. The table 3 is urged downwardly by the spring 7 and the leading edge 8 of the table 3 has an abutment 9 against which the cover board 10 and the backing 11 are positioned.

The opposite end of the arm 5 is connected by linkage 12 and turnbuckles 12' to a foot treadle 22 or it may be rigged up in any other manner so as to be operable by the foot.

While we have shown an arm and foot treadle arrangement for raising and lowering the meeting edge of the table 3, it is to be understood that numerous different ways may be utilized for accomplishing this and that the amount of movement may be adjusted as shown by the turnbuckle or by the use of spacing pins, or the like.

The leading portion of the table 3 preferably carries a strap 13 of resilient material in the form of a cushion.

The table 3 is preferably maintained in a substantially horizontal position although in some instances it may be advisable to tilt the machine to some other position. However, in the descrip-

tion, drawings, and claims, we refer to the table 3 as being in a horizontal position.

Extending vertically over the table 3 is an abutment board 14 in some manner attached to the machine so there will be a space between the bottom edge 14' of the abutment board and the upper surface of the table 3 to accommodate a cover board and its cover. In the embodiment shown and described, the abutment board 14 is mounted directly to the table 3 by means of angle brackets 15 (see Figures 1 and 3).

Mounted on the frame 2 in journals 16 and 17 is a rotating mandrel 18. The mandrel 18 is rotatably driven by a motor 19 through suitable strapping or gearing.

The mandrel 18 carries a plurality of resilient ears 20. The ears 20 are arranged on the mandrel 18 so they project tangentially or at right angles to a radius of the mandrel. In the embodiment illustrated, we have shown the mandrel 18 hexagonal in form with the ears 20 attached to the faces of the mandrel 18 by bolts 21.

The mandrel 18 is rotated in the direction of the arrow (see Figures 5 and 6) so that their ends 20' of the ears 20 follow the direction of rotation.

The ears 20 are fastened adjacent each other and in a helical line around the mandrel 18 with a second helical line, the ears of which are offset or staggered in reference to the ears making up the first helical line (see Figure 7).

The cover board 10 with the underlying cover material 11 is mounted in position below the rotating mandrel 18 by the abutment 9, and the table 3 is tilted upwardly so that the ends 20' of the ears mounted on the rotating mandrel 18 will contact and wipe the cover edge 11' over the edge and onto the opposite surface of the cover board 10 (see Figure 6).

Due to the fact that the ears 20 are in a helical line around the mandrel, there will be a smooth continuous wipage from one end of the edge of the cover board to the other, and inasmuch as the second helical line of ears 20 are staggered in reference to the first, there is no line or break in the wipe due to the juncture of adjoining ears 20.

The ears 20 are formed of relatively stiff, resilient material and we preferably form them of spring steel such as is used in the main spring of a clock. The distance between the cover board 10 and the mandrel 18 when in operation is such that as the ear contacts the edge of the board 10 and cover 11, it is slightly bent rearward so as to present a firm wiping surface against the edge 11' of the cover and force it in close contact with the surface of the cover board 10 (see Figure 6).

The upstanding abutment 14 besides acting as a guard to prevent the operator's hands from getting close to the ears 20 of the mandrel 18, also is used to start the fold of the edge 11' of the cover over the edge of the cover board 10, (see Figure 5).

The mode of operation of our machine is as follows. The cover board 10 and the spine of the book has already been adhesively secured to the cover material 11 with the edges 11' projecting as illustrated in Figure 4. The operator takes this assembly material and by means of a fountain brush or otherwise, moistens the mucilage on the projecting edges 11' of the cover.

The operator then selects which edge of the cover board he desires to commence with and abuts this against the abutment 14 with a slight

wiping motion so as to turn up the edge 11' as shown in the broken lines Figure 5.

The operator then slides the cover board 10 through the space between the bottom 14' of the abutment board and the top of the table 3 until the edge on which he is working abuts against the positioning abutment 9. The operator then presses on the foot treadle 13 which raises the end 8 of the table 3 into the operative position shown in Figure 6. The mandrel 18 is constantly rotating and when the table 3 reaches the position shown in Figure 6, the ends 20' of the ears on the mandrel 18 impinge upon, fold down, and wipe the cover edge 11' against the upper surface of the cover board 10 as shown in Figure 6.

After this operation, the operator takes his foot off the treadle 22 which lowers the table 3 and permits him to remove the cover board with the cover attached and with a side turned-in. The operator then proceeds to repeat this series of operations upon the opposite edge of the cover board and finally on the two remaining edges. The result of the operation is shown in Figure 8, wherein the cover edges 11' are all neatly and firmly folded over the edges of the cover board 10.

The corners of the projecting edge 11' may have previously been cut off to form a neat corner as shown in Figure 8, or a "dutch" corner may have been previously formed by hand.

The resilient cushioning 22 in the end of the table 3 gives a slight cushioning effect, counter-acting the wipe of the ears 20.

While we have shown and described the mandrel 18 as being hexagonal in form, it is to be understood that it may consist of a flat faced prism rotating on its longitudinal axis or any other kind of conformation wherein the wiping ears 20 may be positioned at right angles to a radius comprising the circle of the rotation so as to give an even, smooth, uninterrupted wiping motion to the ends of the ears 20.

From the above, it is apparent that we have provided a turning-in machine which is extremely rugged in construction and wherein cover boards of varying size and thickness may be inserted. The only limitation as to the thickness of the cover board is the size of the slot between the abutment board 14 and the upper surface of the tilting table or support 3.

Other devices such as fountain brushes, moisteners, or the like may be incorporated into our machine. Also, it may be desirable to incorporate a device for turning in round corners. However, our invention relates primarily to the machine for turning-in the cover portion over straight edges of the cover board.

In the following claims where we have used the word "cover" it relates to the cover material covering the cover board and not to the complete and finished cover of a book.

While in the description and drawings we have shown a device for turning in the cover portion on the cover board of a book, it is to be understood that our invention may also be used in turning in the cover on other flat boards, such as chart supports, maps and the like which are not finally folded to form the cover of a book.

It is to be understood that modification may be made in our invention without departing from the spirit thereof, and we do not intend to limit ourselves otherwise than as pointed out in the claims which follow. Having thus described our invention, what we claim as new and desire to secure by Letters Patent is:

1. A machine for turning-in the cover on a board comprising a support for the board and cover, a rotating mandrel having a fixed axial position spaced from and parallel to the support, projecting ears on said mandrel having ends in wiping contact with the surface of the board adjacent an edge thereof when the machine is in operation, said mandrel being at least as long as the edge of the board.

2. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation, said mandrel being at least as long as the edge of the cover board, the portion of the support underlying the edge adjacent the surface to be wiped being movable toward and away from said ear ends.

3. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation, said mandrel being at least as long as the edge of the cover board, the portion of the support underlying the edge adjacent the surface to be wiped being movable toward and away from said ear ends, and being composed of resilient material to form a cushion.

4. A machine for turning-in the cover on a cover board comprising a support for the cover board and cover, a rotating mandrel having a fixed axial position spaced from and parallel to the support, projecting ears on said mandrel having ends in wiping contact with the surface of the cover board adjacent an edge thereof when the machine is in operation, said mandrel being at least as long as the edge of the cover board, said support having an abutment contactable by the edge of the cover board for positioning the same.

5. A machine for turning-in the cover on a cover board comprising a support for the cover board and cover, a rotating mandrel having a fixed axial position spaced from and parallel to the support, projecting ears on said mandrel having ends in wiping contact with the surface of the cover board adjacent an edge thereof when the machine is in operation, said mandrel being at least as long as the edge of the cover board, said support having an upwardly projecting abutment contactable by the edge of the cover board for positioning the same, said abutment underlying the mandrel and parallel thereto and projecting upwardly a distance less than the thickness of the cover board and cover.

6. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation, said mandrel being at least as long as the edge of the cover board, said ears lying on tangents to said mandrel.

7. A machine for turning-in the cover on a cover board comprising a support for the cover board and cover, a rotating mandrel spaced from and parallel to the support, projecting ears on

said mandrel having ends in wiping contact with the surface of the cover board adjacent an edge thereof when the machine is in operation, said mandrel being at least as long as the edge of the cover board, said ears lying on tangents to said mandrel, and said mandrel rotating in a direction away from said ear ends.

8. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation, said mandrel being at least as long as the edge of the cover board, said ears lying on tangents to said mandrel, and said mandrel rotating in a direction away from said ear ends, and positioned above the edge of said cover board with the ear ends wiping from the edge toward the interior of said cover board.

9. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation, said mandrel being at least as long as the edge of the cover board, said ears lying on tangents to said mandrel, and adjacent to each other and together forming at least one helical line around said mandrel.

10. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation said mandrel being at least as long as the edge of the cover board, said ears lying on tangents to said mandrel, and adjacent to each other and forming two helical lines around said mandrel with the individual ears in one helical line in staggered relation to the ears in the other helical line.

11. A machine for turning-in the cover on a cover board comprising a support for the cover board and cover, a rotating mandrel having a fixed axial position spaced from and parallel to the support, projecting ears on said mandrel having ends in wiping contact with the surface of the cover board adjacent an edge thereof when the machine is in operation said mandrel being at least as long as the edge of the cover board, said ears being formed of resilient stiff material.

12. A machine for turning-in the cover on a cover board comprising a support for the cover board and cover, a rotating mandrel having a fixed axial position spaced from and parallel to the support, projecting ears on said mandrel having ends in wiping contact with the surface of the cover board adjacent an edge thereof when the machine is in operation said mandrel being at least as long as the edge of the cover board, said ears being formed of spring steel.

13. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation said

mandrel being at least as long as the edge of the cover board, said mandrel being in the form of a flat faced prism rotatable on its longitudinal axis with the ears fastened to the faces and projecting at tangents to the mandrel.

14. A machine for turning-in the cover on a cover board comprising a support for the cover board and cover, a rotating mandrel spaced from and parallel to the support, projecting ears on said mandrel having ends in wiping contact with the surface of the cover board adjacent an edge thereof when the machine is in operation said mandrel being at least as long as the edge of the cover board, said mandrel being in the form of a flat faced prism rotatable on its longitudinal axis with the ears fastened to the faces and projecting at tangents to the mandrel, said prisms being hexagonal.

15. A machine for turning-in the cover on a cover board comprising a support for the cover board and cover, a rotating mandrel having a fixed axial position spaced from and parallel to the support, projecting ears on said mandrel having ends in wiping contact with the surface of the cover board adjacent an edge thereof when the machine is in operation said mandrel being at least as long as the edge of the cover board, said support being substantially horizontal and carrying a vertical abutment board positioned

5
10
15

in front of the mandrel and spaced above the support a distance greater than the combined thickness of the cover board and cover.

16. A machine for turning-in the cover on a cover board comprising a support for the cover board and cover, a rotating mandrel having a fixed axial position spaced from and parallel to the support, projecting ears on said mandrel having ends in wiping contact with the surface of the cover board adjacent an edge thereof when the machine is in operation said mandrel being at least as long as the edge of the cover board, and an abutment board positioned in front of the mandrel and spaced above the support when in operating position a distance greater than the combined thickness of the cover board and cover.
